H. H. Dyke
ATTORNEY

UNITED STATES PATENT OFFICE.

HENRY J. TYNAN, OF RIDGEWOOD, NEW JERSEY.

BOBBIN-BRAKING MECHANISM.

Application filed September 2, 1924. Serial No. 735,294.

My invention relates to apparatus for braking or checking the rotation of all the bobbins on a creel when the thread being drawn from any one of the bobbins is broken.

5 Apparatus in accordance with my invention may be made use of in a variety of ways in connection with machinery in which strands are drawn simultaneously from a plurality of reels, spools, bobbins and the like, which are designated herein as thread working apparatus. For example, the invention is capable of use with textile apparatus, such as doubling, spinning, twisting, warping and the like machines.

10 The braking apparatus of the present invention is connected with the stop mechanism of the machine to which it is applied, as, for example, the stop mechanism of the thread working textile machine, which stop mechanism operates in the usual well-known fashion and may be of any desired construction. The apparatus of the present invention is operated from the stop mechanism or a part connected thereto, so as to impart 15 braking action to the individual bobbins immediately upon the coming into action of the stop mechanism which stops the feed of the apparatus, and serves to prevent entanglements of the threads with one another or with parts of the machine, which frequently result on existing machines which do not have a braking mechanism such as I have devised and on which the bobbins are left free to turn after the feeding device 20 has been stopped by the stop mechanism. Moreover my braking mechanism permits operation at a much higher rate of speed without such difficulties as looping and entangling of the threads.

25 An important feature of the present invention is the provision of means for the application of substantially equalized braking pressure substantially simultaneously to all of the bobbins upon the creel. Other objects 30 of the invention will be understood from the following description of an embodiment thereof.

In the accompanying drawings Fig. 1 is a front view of a creel having bobbins thereon from which threads are drawn, and provided with braking means for the individual

bobbins. Fig. 2 is a fragmentary view similar to Fig. 1, but showing the braking mechanism in the off position. Fig. 3 is a section on the line 3—3, Fig. 2. Fig. 4 is a detail view of a modification.

The creel illustrated herein comprises bar 10 supported on the machine frame members 11, 11 and having secured thereto the bobbin pins 12 for receiving the bobbins 14 to turn freely thereon as the thread 15 is drawn from them.

The threads 15 from bobbins 14 pass off to any suitable drawing off mechanism through the eyes 16 of the customary fallers 17, which serve in the usual way as the initial operating means for the customary stop mechanism.

In accordance with the present invention, braking means are provided for stopping or 70 checking the rotation of all the bobbins on the creel frame when any of the threads 15 happen to break. Said means serve for checking the rotation of the bobbins in order to prevent the threads which have not been 75 broken flowing from the bobbins. If brakes were not applied to the individual bobbins entanglement of the threads with one another and with the machine parts would result from the bobbins rotating individually and 80 with resulting difficulties to the operator.

Reference character 18 designates a rod connected to a movable part of the stop mechanism, which may be of any well known construction and for this reason need not be 85 described herein in detail. The stop mechanism is of such construction or the connection therewith of such a form as to produce a falling movement of rod 18 when the device drawing thread from a particular creel 90 ceases to act, through the operation of the stop motion immediately related to it.

Rod 18 has adjustably secured to it the collar 20, as by means of a set screw 22. When the apparatus is operating with all the 95 threads intact, collar 20 serves as a support for the brake actuating bar 24, which is connected by parallel links 26, 26 to the creel frame bar 10. A strand 28 of cord, ribbon, tape or the like is connected at or near its 100 ends 30, 32 to the respective ends of the brake actuating bar 24. One or more of these con-

nections may be adjustable, as, for example, one end may be attached by means of the adjustment screw 33. The strand 28 serves to check or impart braking action to the 5 bobbins. In the form shown, the strand 28 is in the form of a round cord and is passed over the hubs or projecting plugs 34 at the ends of the bobbins. Other forms of bobbins and arrangement of strands may, of course, 10 be resorted to so long as the strand can be made use of to serve as a brake against rotation of the bobbins, either by application to the bobbin or to some part turning therewith. For example, I have shown in Fig. 5 the 15 plugs or rollers 34' turning on the pins 12' and having studs 35 adapted to engage in holes 35' provided in the heads of bobbins 14', which are shown in dotted lines in Fig. 20 to denote the disengaged position.

20 At intervals in the length of bar 24, and preferably midway between the bobbin pins 12, said bar 24 is provided with draw rods 36, which are fastened at one of their ends in the bar 24 and are provided at their opposite ends with eyes 38. The cord or strand 28 is passed through the eyes 38 of draw bars 36. A hand operated cam 40 is provided on a convenient part of the apparatus, as, for example, on the frame member 11, and serves for manually operating the bar 24 when desired.

25 The operation of the apparatus described is as follows: Upon any one of the threads from bobbins 14 breaking, the bar 18 falls through the operation of the well known stop mechanism, of which it may form a part or to which it may be connected so as to partake of the movement thereof.

30 The falling of bar 18 permits the brake 40 actuating bar 24 to move downwardly. Bar 24 being supported by the parallel links 26, 26, its downward movement results in a corresponding lateral movement in a direction to pull the cord 28, through the intermediation of draw rods 36, against the bobbins or the hubs thereof, thereby checking their rotation by a fully equalized braking pressure upon the respective bobbins, so that all the bobbins and the flow of thread therefrom 35 are stopped substantially simultaneously and substantially at the same time that the stop mechanism of the machine comes into action to end the drawing off of the threads from the bobbins on the creel.

40 When the rod 18 is raised as by the operator after having tied the broken thread, the creel is restored to its normal operating position shown in Fig. 2, raising the bar 24 and releasing the braking cord 28 from its braking contact with the bobbins. Should the operator desire to free the bobbins from the action of braking cord 28, as, for example, in tying a thread, this may be done by turning the hand operated cam or eccentric 40, which will raise the bar 24 to some extent

and permit any desired release of the braking action of the cord 28. The hand operated cam or eccentric 40 normally hangs free and out of contact with bar 24 when the parts are in the running position shown 70 in Fig. 2. If made use of by the operator while the bobbins are at rest as described, this cam 40 is again restored to its normally free position by raising the bar 24 on starting of the mechanism once more, which carries the bar 24 laterally away from the cam 40. When threads are not being drawn from all the bobbins, empty bobbins may be placed on the pins not in use or cord 28 may be adjusted to compensate for the missing bobbins, as will be readily understood. 75 It will be seen that the invention provides an equalized braking action for the individual bobbins upon the creel and that same may be readily, simply and cheaply constructed; is positive in its operation and effectively prevents the tangling up of threads from bobbins continuing to rotate after the stop mechanism has come into action. The apparatus in accordance with my invention may be provided on creels of various kinds and on textile machinery and thread working apparatus of various kinds, the form illustrated being intended only for affording an understanding of the invention. 80 Modifications and changes may be resorted to within the scope of my claims without departing from the principle of my invention or sacrificing its advantages. 85

I claim:

1. In thread working apparatus equipped with stop mechanism, a creel, a plurality of bobbins thereon from which threads are drawn, a single flexible braking member applied to all the bobbins in the series, and means coming into action upon operation of the stop mechanism for applying tension to the flexible braking member adjacent to each bobbin.

2. In thread working apparatus equipped with stop mechanism, a creel having a series of bobbins thereon from which thread is drawn, a flexible strand braking member for applying braking pressure to the bobbins, and means located at intervals in the length of the flexible strand for moving the flexible braking member against the bobbins.

3. In thread working apparatus equipped with stop mechanism, a creel, a plurality of bobbins thereon from which thread is drawn, a flexible braking member adjacent to the bobbins, and means for pulling the flexible braking member by its ends and also at intervals throughout its length into braking contact with the bobbins.

4. In thread working apparatus equipped with stop mechanism, a creel having a row of bobbin pins arranged substantially on a plane, bobbins on the pins and free to turn thereon, a bar having a plurality of

link supports, whereby upon longitudinal movement of the bar it is also moved transversely with respect to the plane of the bobbin pins, means interconnected with the stop mechanism of the machine for normally supporting said bar and adapted when the stop acts to release said bar and

permit it to move downwardly and transversely, and means operated by the lateral movement of said bar for braking the bobs 10 bins against turning.

In testimony whereof, I have signed my name hereto.

HENRY J. TYNAN.
